DESIGN.

—o—

C. A. DAVIS.

HILT OR HANDLE FOR SWORDS.

No. 19,522.

Patented Dec. 24, 1889.

UNITED STATES PATENT OFFICE.

CHARLES A. DAVIS, OF WASHINGTON, DISTRICT OF COLUMBIA.

DESIGN FOR THE HILT OR HANDLE OF SWORDS.

SPECIFICATION forming part of Design No. 19,522, dated December 24, 1889.

Application filed November 25, 1889. Serial No. 331,558. Term of patent 14 years.

To all whom it may concern:

Be it known that I, CHARLES A. DAVIS, a citizen of the United States, residing at Washington, in the District of Columbia, have invented a certain new and original Design for the Hilts or Handles of Swords, of which the following is a specification.

My invention consists in a novel design for the hilt, handle, or "grip" of a sword, by which latter term I mean to embrace and include the entire class of cut-and-thrust weapons, variously designated as swords, sabers, daggers, knives, foils, &c., used in combat or for practice.

15 The accompanying photographs represent the hilt or handle, Figures 1 and 2 representing different sides of the same.

The design comprises a handle A, formed with ridges *a*, depressions *b*, and an irregular 20 surface *c*, conforming, respectively, more or

less closely to the fingers, thumb, and palm of the hand when the handle or hilt is grasped thereby.

The distinguishing feature of my design is the appearance which it presents to the eye, 25 and which may be best described as that of a plastic body which has been grasped by a human hand and firmly pressed or squeezed, leaving the imprint of the hand.

Having thus described my invention, what 30 I claim is—

The design for the hilt or handle of a sword herein described and shown.

In witness whereof I hereunto set my hand in the presence of two witnesses.

CHARLES A. DAVIS.

Witnesses:

O. M. BALL,
CHARLES G. RINGWALT.
